TIE-BACK CURTAIN

Jeannette Walton Bubeck, Los Angeles, Calif.

Application July 19, 1948, Serial No. 39,509

2 Claims. (Cl. 160—123)

1

The present invention relates to tie-back curtains in general, but has particular reference to a novel means to quickly and accurately determine the correct proportions thereof to ensure harmony and daintiness, in contra-distinction to the present practice of draping huge masses of bunched curtain material along the sides of a window and in such an over-hanging manner as to destroy the prime purpose of the window, which is of course to admit light and to permit of free vision therethrough.

Other than for a sense of privacy obtained by window curtains, their principal purpose is to frame the window opening in a pleasing, harmonious and colorful manner, and the material selected for this purpose usually reflects the taste of the home maker, but aside from these last mentioned considerations, there is still another which enters into the effect obtained by window curtains, and that is the matter of balance and proportion of the component parts of the tie-back curtain, for it is clearly established that in curtains as in other matters, there is a definite balance and proportion to be sought when taken in consideration with the area enclosed by the window frame, that is proper and harmonious, and which if otherwise, is unconsciously recognized as being awkward without being fully aware of the cause of sensed discord.

Being aware of the afore-mentioned considerations, I have evolved a new and easily employed method of correctly proportioning the upper and side panels of a tie-back curtain, for any window size, which is compatible with those considerations of harmony which are based upon physical proportion.

To the above and such other objects, features and advantages thereof as may be noted in the accompanying drawing, the specification and claims, the present invention is directed.

In the drawing:

Figure 1 is a rectilinear piece of curtain material divided equally into four divisions, the portion thereof bounded by dotted lines upon three sides indicates material necessary to form an over-lap or loop through which a curtain rod is adapted to be inserted for support.

Figure 2 is a view showing the upper row of segments of a curtain as delineated by middle and vertical dotted line in Figure 1, the inner and lower corners of the segments being rounded in equal radii.

Figure 3 is a view showing the segments disclosed in Figure 1 in functional relationship to side-panels of the curtain; and,

2

Figure 4 is a view of a completed curtain laid out and proportioned after the method and theory involved in this invention, the curtain here shown as well as the detail set forth in Figures 1, 2 and 4 is that involved in making a curtain for a window having an equal length and breadth.

Figure 5 is a view showing a curtain laid out within the teaching of this invention for a window having a greater length than breadth; and,

Figure 6 is a view of a curtain also laid out within the teaching of this invention but sized for a window of greater breadth than height.

The present invention relates to a new and improved method for quickly, accurately and in harmonious proportion, laying out curtains for standard sized windows and for windows which are not of standard proportion but which on the contrary have been shaped to meet a particular condition present in the structure of the building in which the window is situated.

In describing my invention, I will first describe the method of laying out curtain material for the more unusual type of window as exemplified in Figure 1 which represents a square window, that is, a window of equal length and width. For a window of this type I take a piece of curtain material having a width equal to the width of the area to be curtained, and having a length equal to length of the area to be curtained plus an additional amount of material to the length, as indicated by the dotted lines 10—12 and 14 to allow for an over-lap 16 whereby an elongated pocket is formed for insertion of a curtain supporting rod 18 as shown in Figure 4. I next cut the rectangular piece of material 20 along the vertically disposed dotted line 22 and along the transversely disposed dotted line 24, thus dividing the piece of material 20 into four equally dimensioned pieces of curtain material except for such excess as may be personally desired for the curtain rod supporting pocket 16 afore-mentioned.

I then take the quarter pieces 30 and 32 and divide the width of each of these into three equal spaces along the lower edge 38, placing a mark 40 and 42 thereon to indicate location. Then using a radius 44 having a length equal to one third of the width of the piece 30 or 32, I strike an arcuate curve 46 tangential to the lower edge 38 and to the vertical edge 48 which is coincident with the dotted line 22. The area of the material bounded by the dotted lines 10—12 and 14, and the full line 15 is turned over along line 15 to form the elongated pockets 16 in each of the

sub-pieces 30 and 32 as indicated in the several figures of the drawing.

The sub-pieces 50 and 52 previously cut from the material 20 are each gathered at their one end to a width equal to one third of the length of the lower edge 36 or 38 and are sewed to the pieces 30 and 32 along these lower edges 36 and 38 beginning at the lower and outer corners 54 and 56 and extending inwardly to the points 46 as shown in Figure 3. The lower ends 58 of what 10 may now be termed the side panels 50' and 52' will naturally spread out as shown in Figures 3 and 4, and the curtain thus laid out may be hemmed along its edges for finish or may be provided with single or double ruffles as preferred, 15 but regardless of detailed finish the end product of my invention establishes a curtain proportion substantially as shown in Figure 4, the essence of which is simplicity, neatness and balance while leaving a sufficient amount of the window free for 20 passage of light and air to meet the prime purposes of any window.

In Figure 5 I show a window of conventional form, that is, the window is of greater length than width, and in this instance the afore-described procedure is like-wise followed, while in Figure 6 an odd shaped window is shown, being wider than its height, and in this instance also, the afore-described procedure is followed, that is the total area of the window to be curtained, plus 25 an over-lap as indicated by dotted lines 10-12 and 14, and the full line 15 is first laid out as a rectangle and the piece of material is then cut lengthwise along line 22 or the length thereof regardless of this dimension, and is then cut transversely across and medially of the length making due allowance for the above referred to over-lap. This action divides the material into four pieces 30 of equal size except again for the required over-lap for the purpose of forming the afore-mentioned curtain rod pocket 16. From this point on the curtain is completed as described in the first instance, and this is true regardless of the dimension of the window under consideration.

From the description thus given of my invention when taken in consideration with the drawing, it is believed that it will be apparent that I have devised a convenient and practical method of determining proportions for curtains which is promotional of daintiness and an esthetic sense not found in currently employed methods of laying out curtain material, and at this time I wish to point out that the method involved in the present invention is equally applicable to curtain material formed of celanese, nylon, silk, paper, 35

certain of the sheet plastic material and rubberized fabrics, as well as to cotton prints, although it is recognized that the latter is the more commonly used material for curtain making.

Having thus described my invention in my presently preferred form, that which I desire to protect by Letters Patent, is:

I claim:

1. A two piece curtain, a said curtain being formed in quarter panels, certain of said quarter panels having rounded adjacent lower corners tangential to the bottom edges thereof and to the adjacent inner side edges thereof, and others of said panels, said last mentioned panels being gathered at their one end to a width equal to one third the width thereof, said gathered panels being sewed at their gathered ends to the others of said panels beginning at the lower and outer corners of each thereof and extending inwardly one third the width thereof.

2. A curtain for a window opening, said curtain being formed of dissimilar pair of quarter panels of curtain material, one panel of each pair of panels being matable with a panel of the other of the pairs thereof, the panels of one of the pairs thereof being defined by a rectilinear configuration modified by divergently curved lower adjacent corners, and the panels of the other of the pairs thereof being rectilinear in configuration and having an upper edge gathered to approximately one third the width of each of the panels of the first mentioned pair thereof and being sewed to the lower edges of said first mentioned panels in lateral spaced relationship with respect to one another whereby when so assembled the panels thereof form a recessed covering for the upper portion of a window and a flounced border along the sides of the lower portion of the window.

JEANNETTE WALTON BUBECK.
